UNITED STATES PATENT OFFICE.

ALBERT D. MOORE, OF SOUTH HADLEY FALLS, MASSACHUSETTS

SHUTTLE-BOX FOR LOOMS.

SPECIFICATION forming part of Letters Patent No. 789,443, dated May 9, 1905.

Application filed July 21, 1904. Serial No. 217,523.

To all whom it may concern:

Be it known that I, ALBERT D. MOORE, a citizen of the United States of America, residing at South Hadley Falls, in the county of 5 Hampshire and State of Massachusetts, have invented new and useful Improvements in Shuttle-Boxes for Looms, of which the following is a specification.

This invention relates to looms, and has special reference to the construction of shuttle-boxes, the object of the invention being to construct a shuttle-box of sheet metal, whereby the box may be more cheaply made and the durability thereof greatly increased, the 15 method of construction permitting certain parts thereof, which are subjected to the greatest wear, to be made of metal which can be hardened and tempered before the box is put together.

20 In the drawings accompanying this specification a shuttle-box is shown provided with two compartments only; but it is obvious that the construction may be arranged to comprise as many as are required for the work.

25 Heretofore shuttle-boxes have generally been made of cast metal, usually cast-iron rendered malleable in the well-known manner. These boxes, owing to the nature of the construction, have their interior surfaces all finished off with a file, owing to the fact that the 30 shape of said surfaces renders a machine-finish impracticable. This method of finishing greatly enhances the cost of the boxes. Furthermore, shuttle-boxes as heretofore made 35 of cast metal are a source of constant annoyance and expense, owing to the constant breakage, usually at the mouth of the box, necessitating the stopping of the loom to supply a new box or to repair the broken one. Furthermore, a box may run for some time before the break is discovered, to the great 40 injury of the shuttle, which becomes badly abraded by coming in contact with the broken edges of the box, and, as is well known, this 45 roughened surface of the shuttle is the cause of much breakage of the threads of which the fabric is made.

By means of the present invention a shuttle-box is made much more cheaply and the 50 interior surfaces finished much more perfectly,

as all of the parts may be made of bright stock, and the piece forming the mouth of the shuttle which is subjected to the greatest amount of wear may be hardened, all of which results in great economy in the use of a box 55 made according to this invention as compared with the cast-iron or malleable-iron boxes now in use.

In the drawings forming part of this application, Figure 1 is a perspective view of a 60 shuttle-box in its complete form constructed according to this invention, the binders being omitted. Fig. 2 is a longitudinal sectional plan view in the plane of line 2 2, Fig. 1. Fig. 3 is a transverse sectional view in 65 the plane of line 3 3, Fig. 1. Fig. 4 is a view showing in perspective the component parts of the shuttle-box in separated relation.

Referring to the drawings, *a* and *b* indicate, respectively, the top and bottom plates of the 70 box, each of which in its complete form is shown in Fig. 4, both being identical in shape. The lower edge of each of these plates is turned inward at right angles to the plane of the body thereof, forming the flange *c*. The 75 mouth of the shuttle-box, to which one end of the plates *a* and *b* are secured, is made of two pieces, (shown in their separated relation in Fig. 4,) one of these pieces forming the front and the other the back side of the mouth-piece. The latter consists of a flat metal plate *d*, having at or near each corner thereof and formed integrally therewith an upstanding leg *e*, *f*, *g*, and *h*, the front plate *j* being provided with two legs *k* and *m*, located centrally 80 of the two sides of the plate integral therewith, and they are of such width that they will fit closely, one between the legs *e* and *h* and the other between the legs *g* and *f*, when the parts are applied one to the other, as shown 85 in Fig. 1. The stock of which these plates *d* and *j* are made is of the same thickness, to the end that when the two parts are put together in the manner shown in Fig. 1 the legs *h* and *e* of one plate and *k* of the other will constitute a continuous side surface for the mouth-piece and the similarly-located legs on the other side of said plates a like surface. It 90 will be noted that the ends of the legs *h* and *g* will fit into the notches *o* and *p*, cut in the 95 100

side of the plate *d*, and the end of the legs *e* and *f* of the plate *d* will fit into similar notches *r* and *s* in the opposite side of the plate *j*. In the ends of the legs *e* and *f* a rectangular notch *t* is cut, whose depth is equal to the thickness of the plate *j*, said notches forming a shoulder on which the rear end of said plate may rest.

The flanges *c* on the top and bottom plates *a* and *b* terminate at the rear edge of the plate *d*, and that part of said plates beyond the end of the flange extends into the mouthpiece of the shuttle-box and is provided with holes, as *v*, which register with holes *w* in the legs of the plate *d* and in the legs of the plate *j*, whereby the plates *a* and *b* may be riveted securely to the mouthpiece and whereby the ends of said plates which lie within the mouthpiece constitute a binding-plate for the two parts of the mouthpiece.

When the legs on the plates *d* and *j* are bent up at right angles thereto, the bend is formed in such manner that the plane of the inner surface of the legs will be located outside the plane of the edge of the plate a distance substantially equal to the thickness of the plates *a* and *b*, and on the lower edge of the plates a projection *x* is formed, which will fit in between the edge of the plate *d* and the inner surface of the ends of the legs *k* and *m* of the plate *j*. This constitutes a lock for the plates and takes much of the shearing strain off the rivets.

The forward edge of the plate *j* is outwardly curved, as indicated at *y*, whereby the mouthpiece is given the usual flare on this side, to the end that should the shuttle vary slightly in its flight it will be properly directed into the box. The forward edge of the plate *d* is preferably reinforced by means of a strip *3*, which is riveted thereto on the under side, said piece extending across the front edge of the plate, which is thereby doubled in thickness, and after being so riveted to said edge the latter is ground off to a rounded form in cross-section to prevent any injury to the shuttle on entering the box.

At the rear end of the shuttle-box the top and bottom plates are secured together by a front plate only, lettered *4*, having rectangularly-arranged integral sides *5*, the distance between which is the same as the distance between the legs *k* and *m*. The rear ends of the top and bottom plates *a* and *b* are located inside of the sides *5* of the plate *4*, the end of each of the plates having a tongue *6* thereon which enters slots *7* in the upper surface of the plate *4*, the sides *5* and the ends of the plates *a* and *b* being riveted together. On the forward end of each of the top and bottom plates are the tongues *8* and *9*, the latter extending far enough above the surface of the plate *j* to constitute, together with the piece *10* in the center of the plate *j*, suitable supports for the rod, (not shown,) which ex-

tends from one side of the shuttle-box to the other over the ends of the shuttle-binders, whereby the outward movement of the latter may be limited. It will be observed that notches *o*, *r*, *p*, and *s*, formed in the plate *j*, are deep enough to receive the tongues *8* and *9* on the plates *a* and *b*, as well as the legs of the plate *d*, and still leave the outer surface of the latter flush with the sides of the legs *k* and *m*. The rear ends of the usual shuttle-binders (not shown) may be supported on a rod carried in the ears *12* on the plate *4*, the latter being cut away, as at *14*, between the ears *12* to permit that end of the shuttle-binder to swing freely on its hinge. Toward the rear end of the plate *4* ribs *15* are struck up on the surface of the plate substantially in line with each of the ears *12* and are made to receive between them the end of a flat shuttle-binder spring, a screw entering the hole *16* to secure said spring to the plate *4*. This construction may be the same as in ordinary shuttle-boxes. Where the tongues *6* project through the slots *7*, they may be made long enough to be headed over on the plate, if desired.

The foregoing description is that of the construction of the shuttle-box proper, and the box may be subdivided into as many longitudinal compartments as the nature of the work to which it is to be adapted requires. By the introduction between the plates *a* and *b* of one or more partitions *20*, having a suitable flange *21* extending along the bottom edge thereof, (said partitions being parallel with the plates *a* and *b* and said flange being in the same plane as the flanges *c*,) a shuttle-box adapted to carry any desired number of shuttles may be provided. These partitions may be made and are preferably made, as shown in Fig. 4 particularly, of a sheet of metal which when bent upon itself will substantially equal in thickness the plates *a* and *b*, and in bending the two thicknesses of metal together the rib *21* may be formed along the lower edge thereof in the well-known manner by leaving the rib-forming portion tubular and then shutting it up in a pair of dies to form the flange at right angles to the body of the partition.

That end of the partition which divides the mouthpiece to form a compartment on each side thereof is provided with tongues *24*, which enter slots *25*, punched through both the plates *d* and *j*, as shown in Fig. 4, the ends of these tongues being headed over on said plates to secure the partitions firmly thereto. Similar tongues *26* are formed on the rear ends of the partition, but only on one side thereof, contiguous to the plate *4*, and which enter the slots *28* in said plate, the tongues being headed over on the plate.

The rear edge of the plate *d* has recesses *30* cut therein to provide space for the proper throw of the picker.

It is clear from the foregoing description that a box constructed in the manner described will have all of the characteristics of the shuttle-box now in vogue as far as the shape there-
5 of is concerned, the manner of supporting the box, and the manner of applying the shuttle-
binders.

If the ends of the shuttle-binders which lie on the plate *j* are narrower than the space be-
10 tween the projections 9 and 10, a block 31 may be applied to the inner surface of the projec-
tions 9 and riveted thereto, whereby said space may be reduced to substantially the width of the ends of the binders.

15 Having thus described my invention, what I claim, and desire to secure by Letters Patent of the United States, is—

1. A shuttle-box for looms consisting of top and bottom plates of sheet metal each having 20 an inturned flange along the bottom edge; a mouthpiece comprising a front and back plate having legs thereon to extend past one another transversely of the top and bottom plates, the latter and said mouthpiece being 25 secured together, a second front plate extending across the opposite end of the top and bottom plates, and means to secure the latter and said second front plate rigidly together.

2. A shuttle-box for looms consisting of top 30 and bottom plates of sheet metal each having an inturned flange along the bottom edge there-
of, a mouthpiece comprising front and back plates having legs thereon extending past one another and constituting a rectangular mouth-
35 piece, there being notches in the edges of each of said plates to receive the legs of the other plate; lugs on said top and bottom plates also extending into said notches, and means to secure the plates rigidly to the mouthpiece, to-
40 gether with a second front plate for the opposite ends of the top and bottom plates, and legs to embrace the plates.

3. A shuttle-box for looms comprising top and bottom plates of sheet metal each having 45 an inturned flange along the bottom edge there-
of, a rectangularly-shaped mouthpiece fitting over one end of said plates, a U-shaped plate to fit over the opposite ends of said plates and transversely across the sides thereof, and 50 means to secure the ends of said top and bottom plates respectively to said mouthpiece and to said U-shaped member.

4. A shuttle-box for looms comprising top and bottom plates of sheet metal each having 55 an inturned flange along the bottom edge there-
of, a rectangularly-shaped mouthpiece fitting over one end of said plates, a U-shaped plate to fit over the opposite ends of said side plates and transversely across the sides thereof, and 60 means to secure the ends of said top and bottom plates respectively to said mouthpiece and to said U-shaped member.

65

tion on both sides thereof in the plane of the flanges on the top and bottom plates, said partition having an interlocking engagement with said mouthpiece and with said U-shaped member.

70

5. A shuttle-box for looms comprising top and bottom plates of sheet metal, each having an inturned flange along the bottom edge thereof, a rectangularly-shaped mouthpiece into which one end of each of said plates ex- 75 tends, tongues on said plates extending through the wall of the mouthpiece, and be-
yond the surface of the latter, a U-shaped plate into which the opposite ends of the top and bottom plates extend, and means to se- 80 cure the latter to the sides of said U-shaped plate; ears on the latter to support the usual shuttle-binder, the opposite end of which is located between said tongues.

6. A shuttle-box for looms consisting of two 85 side plates of sheet metal each having an in-
turned flange along the bottom edge thereof; a mouthpiece comprising top and bottom plates having legs thereon extending past one another and constituting a rectangular mouthpiece 90 there being notches in the edges of each of said plates to receive the legs of the other plate; thumbs on said side plates also extend-
95 ing into said notches, and means to secure the side plates rigidly to the mouthpiece; together with a second top plate for the opposite ends of the side plates and legs to embrace the plates.

7. A shuttle-box for looms comprising two 100 side plates of sheet metal each having an in-
turned flange along the bottom edge thereof, a rectangularly-shaped mouthpiece fitting over one end of said side plates, a U-shaped plate to fit over the opposite ends of said side plates and transversely across the sides thereof, and 105 means to secure the ends of said side plates respectively to said mouthpiece and to said U-shaped member.

8. A shuttle-box for looms comprising two 110 side plates of sheet metal each having an in-
turned flange along the bottom edge thereof, a rectangularly-shaped mouthpiece fitting over one end of said side plates, a U-shaped plate to fit over the opposite ends of said side plates and transversely across the sides thereof, and 115 means to secure the ends of said side plates re-
spectively to said mouthpiece and to said U-
shaped member, together with a partition lo-
cated midway between said side plates, par-
allel therewith; a flange extending along the 120 bottom edge of said partition on both sides thereof in the plane of the flanges on the side plates, said partition having an interlocking engagement with said mouthpiece and with said U-shaped member.

9. A shuttle-box for looms comprising two 125 side plates of sheet metal, each having an in-
turned flange along the bottom edge thereof, a rectangularly-shaped mouthpiece into which one end of each of said side plates extends, 130

tongues on the side plates extending through the wall of the mouthpiece, and beyond the surface of the latter, a U-shaped plate into which the opposite end of the side plate extends and means to secure the latter to the sides of said U-shaped plate; ears on the latter to support the usual shutter-binder, the

opposite end of which is located between said tongues.

ALBERT D. MOORE.
